UNITED STATES PATENT OFFICE.

ARTHUR MENG, OF CLEVELAND, OHIO.

DESIGN FOR A SPECTACLES DISPLAY HOLDER.

Application filed September 11, 1922. Serial No. 3,684. Term of patent 7 years.

To all whom it may concern:

Be it known that I, ARTHUR MENG, a citizen of Germany, residing at Cleveland, in the county of Cuyahoga and State of Ohio, have invented a new, original, and ornamental Design for Spectacles Display Holder, of which the following is a specification, reference being had to the accompanying drawing, forming part thereof.

The figure in the drawing is a front elevation of a spectacles display holder, showing my new design.

I claim:

The ornamental design for a spectacles display holder, as shown.

ARTHUR MENG.
